UNITED STATES PATENT OFFICE.

ARCHIE J. METZ, OF CINCINNATI, OHIO.

LOCK BLOCK FOR STEEL BEDSPRINGS.

1,412,482.

Specification of Letters Patent. Patented Apr. 11, 1922.

Application filed July 11, 1921. Serial No. 483,755.

To all whom it may concern:

Be it known that I, ARCHIE J. METZ, a citizen of the United States of America, and a resident of Cincinnati, in the county of 5 Hamilton and State of Ohio, have invented a new and useful Improvement in a Lock Block for Steel Bedsprings, of which the following is a specification.

My invention relates to metal bed construction, and to the means for supporting the spring mattress frames carried thereby, more particularly relating to the casting member employed for connecting the side rails with head and foot iron cross-bars to 15 which the so called spring bed bottoming or mattress supporting wire structure is connected.

An object of my invention is to provide mounting means of the type referred to 20 wherein the members are positively precluded from separating.

Another object of my invention is to provide a simple and efficient construction of the parts.

25 These and other objects are attained by the means described herein and disclosed in the accompanying drawings, in which—

Fig. 1 is an elevation of a coupling member, or bracket, made in accordance with my 30 invention, illustrating one of the angle iron cross-bars in proper position with relation thereto.

Fig. 2 is an end elevation of the parts shown in Fig. 1.

35 Fig. 3 is a fragmental view showing the manner of mounting the angle iron on the bracket.

The bracket A is attached to the side bar B of the bed frame in any suitable manner, 40 such as providing the bracket with a socket or bore α within which the end of the side bar B extends. The end of the bracket A, spaced from the side bar B, has a block α' formed upon it. The block has a slot α^2 45 extending therethrough transversely to, or at right angles to, the side bar B when mounted on the bracket. The inner portion α^3 of the block, or in other words that portion of the block formed immediately

50 adjacent the central part or arm α^4 of the bracket, extends upwardly beyond the slot α^2 and has its outer face α^5 disposed at substantially right angles to the axis of the bore α in the bracket and extending above 55 the slot α^2 . The outer portion α^6 of the block extends from the inner portion of the block

like a flange, terminating about midway of the height of the block and has its inner face α^7 extending in substantial parallelism with the face α^5 formed on the block. The 60 face α^8 formed on the inner portion α^3 of the block, lying in the slot α^2 and disposed opposite to the face α^7 , extends downwardly and toward the socket formed in the bracket. A stud or pin α^9 extends from the face α^5 65 of the block portion α^3 and extends over the slot α^2 . An angle iron D has formed on its one side plate d , a hole d' of sufficient size to accommodate the stud α^9 . The side plate d of the angle iron is made of a thickness 70 substantially equal to the perpendicular distance between the parallel faces α^5 and α^7 formed on the block. The face α^8 formed on the block interiorly to the slot, is inclined at such an angle that the free end or lower 75 end d^2 of the side plate d may be projected into the slot without interference from the stud α^9 . After the lower end of the side plate has been inserted in the slot, the side plate is moved toward the innermost portion 80 α^3 of the block so that the opposite sides of the side plate engage the faces α^5 and α^7 , whereupon the stud α^9 is projected into the slot d' formed in the angle plate. The other side plate d^3 of the angle iron has attached 85 to it the springs C, such as are commonly employed in the construction of bed springs. The springs C retain the angle plate in firm engagement upon the faces α^5 and α^7 of the block and the studs α^9 prevent any lateral 90 displacement or movement of the angle iron.

The avoidance of lateral movement of the angle iron is of prime importance, because during the shipment of bed springs, unless the angle iron is retained as shown in this 95 application, or else riveted to the bracket A, the rough handling and jolting accorded the springs cause the angle iron to separate from the bracket, thereby disassociating the entire bed spring. After the angle iron is 100 mounted upon a block and the springs C are stretched between the angle irons mounted at opposite ends of the side bars B, the rough handling and jolting of the springs will not cause the parts to separate. 105

What I claim is:

In a corner member for bed springs or mattress supporting frames and the like, the combination of a bracket attachable to the side rail of the structure, a block mounted on the bracket spaced from the side rail, a flange formed on the block extending 110

transversely to the side rail whereby a slot is provided between the flange and the balance of the block, the wall of the slot opposite the flange extending downwardly away from the flange and the wall of the block above said slot extending in substantial parallelism with the wall of the slot formed on the flange, studs extending from the block above the slot, and a cross-bar, to which the mattress supporting structure is attached, having a slotted side plate of a

thickness substantially equal to the perpendicular distance between the parallel faces on the block, the slots in the plate being adapted to accommodate the studs on the block, and the opposite sides thereof engaging the parallel faces formed on the block.

In testimony whereof, I have hereunto subscribed my name this 25th day of June, 1921.

ARCHIE J. METZ.
